[57] CLAIM

The ornamental design for a bag stand, as shown and described.

DESCRIPTION

FIG. 1 is a right side elevational view of a bag stand showing our new design, the left side being a mirror image of that shown;

FIG. 2 is a top plan view thereof;

FIG. 3 is a bottom plan view thereof;

FIG. 4 is a rear elevational view thereof; and,

FIG. 5 is a front elevational view thereof.

The broken line showing of a partial golf bag in FIG. 1 is for illustrative purposes only and forms no part of our design.
